SHARPENER FOR ENDLESS BAND BLADE BREAD SLICING MACHINE

Kenneth Visnaw, Saginaw, Mich., assignor to Bettendorf Bakery Equipment Co., Bettendorf, Iowa, a corporation of Iowa

Filed Sept. 22, 1959, Ser. No. 841,511

11 Claims. (Cl. 51—247)

This invention relates to a honing or sharpening device for slicing machines of the type having a plurality of endless slicing bands turning on and reaching between upper and lower drums, the two reaches of each band between the drums each having a twist of 180°. There may be one or more upper drums and one or more lower drums, and the 180° total twist of each reach may be all in the same direction, or may be 90° in one direction of twist and then 90° in the opposite direction of twist.

The invention contemplates the provision of a sharpener assembly which is substantially self-contained and may be readily mounted in association with the base frame of a bread slicing machine to sharpen one side of each blade. It will usually be desirable to provide two of the devices contemplated by the invention at different locations in association with the base frame in order to provide for sharpening of both sides of each blade. The invention contemplates the provision of a cylindrical abrasive member carried on a sharpener carriage and mounted for continuous rotation relative thereto but adapted to be oscillated into and out of blade-engaging condition by bodily movement together with the sharpener carriage and further adapted to be bodily reciprocated back and forth together with the sharpener carriage, motor means being provided in driving association with the cylindrical abrading member and with a linkage for reciprocating the sharpener carriage.

A subsidiary object of the invention is to provide the above organization of elements in association with means for controlling the motion of the abrading member as it is moved into contact with the blades to be sharpened in a manner which will appear more fully below.

A general object of the invention is to provide a blade sharpener device of the general class described which is inexpensive to manufacture and is effective, efficient and reliable in operation.

These and other objects and advantages of the invention will appear more fully from the following description of an example of the invention taken together with the accompanying drawings, in which:

Figure 1 is a side elevation of a band blade bread slicing machine in which the invention is employed.

Figures 2 and 3 are enlarged views showing, respectively, the upper right and lower left portions of Figure 1.

Figure 4 is a fragmentary view taken from the plane of line 4—4 in Figure 2.

Figure 5 is a perspective view of a sharpener carriage assembly and associated stationary shaft employed in the illustrated example of the invention and also seen in part in Figures 2—4.

Figure 6 is a fragmentary cross-section of the cylindrical abrading member and associated bearing structure shown in Figure 5.

Figure 7 is an end view of the apparatus as seen in Figure 5.

Figure 8 is a fragmentary elevational view taken on line 8—8 in Figure 7 and illustrating two different relative positions of a portion of the apparatus.

2

Shown in Figure 1 is a side elevation of a conventional endless blade type bread slicing machine including a base frame generally indicated by the reference numeral 10, a first drum 11 at the upper portion of the apparatus, and a second drum 12 at the lower portion of the apparatus. Each of the drums 11 and 12 is rotatably mounted on the base frame 10. The drum 12 is powered from a suitable motor 13. A plurality of endless slicing blades 14 turn on and reach between the drums 11 and 12 in a well-known manner. Each of the slicing blades 14 has first and second reaches, 15 and 16 respectively, which extend from a position in contact with and tangent to the first drum 11 to a position in contact with and tangent to the second drum 12. Each of the first and second reaches 15 has a twist of 180° therein. Each reach is guided by a pair of guide fingers 17 and 18 in a well-known manner so that the portion of the reach extending between the guide fingers 17 and 18 includes substantially no twist, the majority of the twist therefore occurring between the roll 11 and the guide finger 17 or the roll 12 and the guide finger 18. All this is well known.

According to the invention, there may be provided sharpener assemblies mounted in the manner described below on the base frame 10, each sharpener assembly being provided with sharpening apparatus adapted to be brought into sharpening association with one side of each of the bands 14 at the cutting edges thereof. The locations of these sharpener assemblies are indicated diagrammatically in Figure 1 by the reference numerals 21 and 22. The sharpener assemblies to be positioned at 21 and 22 are illustrated on a small scale in Figures 2 and 3, respectively. In Figure 2, such apparatus is generally indicated by the reference numeral 23; and in Figure 3, by the reference numeral 24.

35 The sharpening assemblies illustrated in Figures 2 and 3 are substantially identical and each comprises a sharpener carriage 30, a cylindrical abrading member 31, a stationary mounted shaft 32, and a number of other identical or equivalent elements. Since the sharpener apparatus of Figures 2 and 3 are substantially identical, the remainder of this description will concern itself only with the description of the apparatus seen in Figure 2, it being understood that such description will also serve to describe the apparatus of Figure 3.

40 45 The sharpener carriage 30 in the illustrated assembly comprises a sleeve portion 33 which is received for sliding and oscillating motion on the stationary shaft 32. The stationary shaft 32 is received in suitable mounting brackets 34 which are bolted to the base frame 10. The cylindrical abrading member 31 comprises a plurality of cylindrical segments 36 received on a shaft 37, the reduced ends of which are rotatably mounted in end bearing assemblies 38 (see Figures 5 and 6). Each end bearing assembly 38 is bolted to the tie plate 39 which is affixed to the sleeve 33. A sheave 40 is in driving association with the shaft 37.

50 It will be seen that the cylindrical abrading member 31 is, in fact, rotatably mounted on the sharpener carriage 30 for reciprocation and oscillation bodily therewith, and is rotatable relative thereto about an axis parallel to the stationary shaft 32, that is, parallel to the direction of reciprocation of the sharpener carriage. It will be seen that the oscillatory motion of the abrading member 31 as it moves bodily with the sharpener carriage accomplishes movement of the abrading member 31 into and out of engagement with the blades. One of the reaches 16 of one of the blades 14 is seen in Figure 4 and also seen in this figure is the abrading member 31 in the relative positional relationship which it bears with respect to the reach 16. 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 of the reach 16 at the portion thereof adjacent the abrading member 31. This angle might be typically about seven degrees.

In the illustrated apparatus, a pair of spaced guide plates 46 and 47 are fixed to the stationary shaft 32 and have apposite guiding faces normal to the stationary shaft. A drive shaft 48 is mounted on the sharpener carriage 30 in the manner illustrated most clearly in Figure 5. The drive shaft 48 extends radially outwardly with respect to the stationary shaft 32. An eccentric wheel 49 is mounted eccentrically on the drive shaft 48 and is engaged between the guiding faces of the guide plates 46 and 47. It will be seen that this linkage accomplishes reciprocation of the sleeve 33 on the shaft 32 by a mechanical relationship which is independent of oscillatory movement of the sharpener carriage 30 and abrading member 31 about the stationary shaft 32.

Motor means is provided in driving association with the cylindrical abrading member 31 for powering the rotation thereof relative to the sharpener carriage 30 and also in driving association with the carriage reciprocating linkage means including in the illustrated embodiment the eccentric wheel 49 and drive shaft 48. In the illustrated embodiment a motor 55 is carried bodily on the sharpener carriage 30 and drives the sheave 40 through a belt 56. The other end of the shaft of the motor 55 powers the drive shaft 48 through a suitable speed reducing linkage including the worm 57 and spur 58.

Yielding means is provided which normally biases the sharpener carriage 30 at oscillatory positioning of the abrading member out of contact with the blades. In the illustrated embodiment this means comprises a spring 60 which biases a head or abutment 61 upwardly as viewed in Figure 4. Actually, the oscillatory positioning of the abrading member 31 as seen in Figure 4 is even further away from the blade reach 16 than the position imposed by the spring 60, since in this particular view the carriage 30 and particularly the bearing assembly 38 and tie plate 39 are shown as being out of contact entirely with the member 61. This relationship results, for example, if the center of gravity of the sharpener assembly 23 as seen in Figure 2 is such that it tends to maintain itself at a leftmost oscillatory position as seen in Figure 2 due to the center of gravity being located to the left of the center of the shaft 32. It will be understood, however, that even if this is not the case, the spring 60 and abutment 61 act against the underside of the members 38 and 39 to normally hold the abrading member 31 out of engagement with the blade reach 16.

The oscillatory position of the sharpener carriage 30 and abrading member 31 may be fixed by suitable handle means conventionally extending sidewise outwardly past the side of the base frame 10. As illustrated, the handle may comprise merely a bent plate or rod 65 bolted to one of the bearing assemblies 38.

The spring 60 and abutment member 61 are based on a fixed tie member 66 which may be bolted to the base frame 10, as seen most clearly in Figure 4. If the handle 65 is manipulated in such a manner as to bring the abrading member too rapidly into contact with the reach 16, damage or injury, including dangerous breakage of the blade 14, may result. To this end the velocity of movement of the stem 69 carrying the abutment 61 is limited, at least in the downward direction as viewed in Figure 4, by a suitable device, such as a dashpot 68 or other velocity limiting means.

Suitable adjustment means such as the nuts 71 and 72 in association with a threaded stem 73 may be provided to adjust the datum position of the assembly including the spring 60, abutment member 61, and dashpot 68.

The operation of the illustrated apparatus is as follows. When it is desired to sharpen blades, which may be at intervals of some several hours or several days, the handle 65 associated with the upper sharpener assembly is pushed downwardly to the left as seen in Figure 2 to bring the associated abrading member 31

slowly into contact with one side of the cutting edge of the array of band blades, this movement being relatively lightly opposed by the spring 60 and the velocity of this movement being limited by the dashpot 68. The handle 65 is thereupon moved upwardly and to the right as seen in Figure 2 or is simply released to bring the abrading member 31 out of contact with the band blade 14.

The lowermost sharpener assembly seen in Figure 3 is similarly actuated.

The sequence of operations may be repeated several times and in any combination. It may be desirable to actuate the upper sharpener assembly and then the lower sharpener assembly through several cycles, or to actuate one several times in succession and then actuate the other several times in succession.

The invention is not restricted to the slavish imitation of each and every one of the details described above which have been set forth merely by way of example with the intent of most clearly setting forth the teaching of the invention. Obviously devices may be provided which change, eliminate or add certain specific structural details without departing from the invention.

What is claimed is:

1. The combination with a base frame, first and second parallel, spaced-apart drum means rotatably mounted on said base frame, and endless slicing bands turning on and reaching between said first and second drum means, said slicing bands each having a cutting edge and said slicing bands each having first and second reaches both of which extend from a position in contact with and tangent to said first drum means to a position in contact with and tangent to said second drum means, and each of said first and second reaches having a twist of 180 degrees therein, of: a stationary shaft on said base frame extending parallel to the axes of said drum means, a sharpener carriage having a sleeve portion received for sliding and oscillating motion on said stationary shaft, a cylindrical abrading member rotatably mounted on said sharpener carriage for reciprocation and oscillation bodily therewith and for rotation relative thereto about an axis parallel to said stationary shaft, said oscillatory motion of said abrading member bodily with said sharpener carriage accomplishing movement of said abrading member into and out of engagement with one side of one edge of said bands, spaced guide plates fixed to said stationary shaft and having apposite guiding faces normal to said stationary shaft, a drive shaft mounted on said sharpener carriage and extending radially outwardly with respect to said stationary shaft, an eccentric wheel eccentrically mounted on said drive shaft and engaged between said guiding faces for accomplishing reciprocation of said sleeve on said shaft by a mechanical relationship which is independent of said oscillatory movement of said sharpener carriage about said stationary shaft, motor means carried bodily on said sharpener carriage and in driving association with said cylindrical abrading member for powering the rotation thereof relative to said sharpener carriage and in driving association with said drive shaft, yielding means normally biasing said sharpener carriage for oscillatory positioning of said abrading member out of contact with said blades, means limiting the angular velocity of said oscillatory movement of said abrading member into contact with said blades, said two last-named means including an abutment shaft positioned for engagement by said sharpener carriage toward the one limit of oscillatory movement of the carriage relative to said sharpener carriage which corresponds to engagement of said abrading member with said bands, spring means biasing said abutment shaft to yieldingly oppose displacement upon engagement by said carriage, and a dashpot limiting the rate of displacement of said shaft against the biasing of said spring.
2. The combination with a base frame, first and second parallel, spaced-apart drum means rotatably mounted on said base frame, and endless slicing bands turning on and reaching between said first and second drum means, said

slicing bands each having a cutting edge and said slicing bands each having first and second reaches both of which extend from a position in contact with and tangent to said first drum means to a position in contact with and tangent to said second drum means, and each of said first and second reaches having a twist of 180 degrees therein, of: a first sharpener assembly including a sharpener carriage, means mounting said sharpener carriage on said base frame for reciprocation in a given direction transversely of said bands and for oscillation in planes normal to said direction, said given direction being parallel to the axes of said drum means, a cylindrical abrading member rotatably mounted on said sharpener carriage for reciprocation and oscillation bodily therewith and for rotation relative thereto about an axis parallel to said given direction, said oscillatory motion of said abrading member bodily with said sharpener carriage accomplishing movement of said abrading member into and out of engagement with one side of one edge of said bands, linkage means for reciprocating said sharpener carriage, motor means in driving association with said cylindrical abrading member for powering the rotation thereof relative to said sharpener carriage and in driving association with said carriage-reciprocating linkage means for actuation thereof, a second sharpener assembly including a second sharpener carriage, means for mounting said second sharpener assembly on said base frame for reciprocation in a given direction transverse of said bands and for oscillation in planes normal to said direction, said given direction being parallel to the axes of said drum means, a second cylindrical abrading member rotatably mounted in said second sharpener carriage for reciprocation and oscillation bodily therewith and for rotation relative thereto about an axis parallel to said given direction, said oscillatory motion of said abrading member bodily with said second sharpener carriage accomplishing movement of said second abrading member into and out of engagement with the aforesaid one edge of said bands on the side thereof other than the aforesaid one side, second linkage means for reciprocating said second sharpener carriage, motor means in driving association with said second cylindrical abrading member for powering the rotation thereof relative to said second sharpener carriage and in driving association with said second carriage-reciprocating linkage means for actuation thereof.

3. The combination with a base frame, first and second parallel, spaced-apart drum means rotatably mounted on said base frame, and endless slicing bands turning on and reaching between said first and second drum means, said slicing bands each having a cutting edge and said slicing bands each having first and second reaches both of which extend from a position in contact with and tangent to said first drum means to a position in contact with and tangent to said second drum means, and each of said first and second reaches having a twist of 180 degrees therein, of: a stationary shaft on said base frame extending parallel to the axes of said drum means, a sharpener carriage having a sleeve portion received for sliding and oscillating motion on said stationary shaft, a cylindrical abrading member rotatably mounted on said sharpener carriage for reciprocation and oscillation bodily therewith and for rotation relative thereto about an axis parallel to said stationary shaft, said oscillatory motion of said abrading member bodily with said sharpener carriage accomplishing movement of said abrading member into and out of engagement with one side of one edge of said bands, linkage means for reciprocatably sliding said sharpener carriage back and forth on said shaft, motor means carried bodily on said sharpener carriage and in driving association with said cylindrical abrading member for powering the rotation thereof relative to said sharpener carriage and in driving association with said carriage-reciprocating linkage means for actuation thereof, yielding means normally biasing said sharpener carriage for oscillatory positioning of said abrading member out of contact with said blades.

4. The combination with a base frame, first and second parallel, spaced-apart drum means rotatably mounted on said base frame, and endless slicing bands turning on and

reaching between said first and second drum means, said slicing bands each having a cutting edge and said slicing bands each having first and second reaches both of which extend from a position in contact with and tangent to said first drum means to a position in contact with and tangent to said second drum means, and each of said first and second reaches having a twist of 180 degrees therein, of: a sharpener carriage, means mounting said sharpener carriage on said base frame for reciprocation in a given direction transversely of said bands and for oscillation in planes normal to said direction, said given direction being parallel to the axes of said drum means, a cylindrical abrading member rotatably mounted on said sharpener carriage for reciprocation and oscillation bodily therewith and for rotation relative thereto about an axis parallel to said given direction, said oscillatory motion of said abrading member bodily with said sharpener carriage accomplishing movement of said abrading member into and out of engagement with one side of one edge of said bands, linkage means for reciprocating said sharpener carriage, motor means in driving association with said cylindrical abrading member for powering the rotation thereof relative to said sharpener carriage and in driving association with said carriage-reciprocating linkage means for actuation thereof, yielding means normally biasing said sharpener carriage for oscillatory positioning of said abrading member out of contact with said blades.

5. The combination with a base frame, first and second parallel, spaced-apart drum means rotatably mounted on said base frame, and endless slicing bands turning on and reaching between said first and second drum means, said slicing bands each having a cutting edge and said slicing bands each having first and second reaches both of which extend from a position in contact with and tangent to said first drum means to a position in contact with and tangent to said second drum means, and each of said first and second reaches having a twist of 180 degrees therein, of: a stationary shaft on said base frame extending parallel to the axes of said drum means, a sharpener carriage having a sleeve portion received for sliding and oscillating motion on said stationary shaft, a cylindrical abrading member rotatably mounted on said sharpener carriage for reciprocation and oscillation bodily therewith and for rotation relative thereto about an axis parallel to said stationary shaft, said oscillatory motion of said abrading member bodily with said sharpener carriage accomplishing movement of said abrading member into and out of engagement with one side of one edge of said bands, linkage means for reciprocatably sliding said sharpener carriage back and forth on said shaft, motor means carried bodily on said sharpener carriage and in driving association with said cylindrical abrading member for powering the rotation thereof relative to said sharpener carriage and in driving association with said carriage-reciprocating linkage means for actuation thereof, yielding means normally biasing said sharpener carriage for oscillatory positioning of said abrading member out of contact with said blades.

6. The combination with a base frame, first and second parallel, spaced-apart drum means rotatably mounted on said base frame, and endless slicing bands turning on and reaching between said first and second drum means, said slicing bands each having a cutting edge and said slicing bands each having first and second reaches both of which extend from a position in contact with and tangent to said first drum means to a position in contact with and tangent to said second drum means, and each of said first and second reaches having a twist of 180 degrees therein, of: a sharpener carriage, means mounting said sharpener carriage on said base frame for reciprocation in a given direction transversely of said bands and for oscillation in planes normal to said direction, said given direction being parallel to the axes of

said drum means, a cylindrical abrading member rotatably mounted on said sharpener carriage for reciprocation and oscillation bodily therewith and for rotation relative thereto about an axis parallel to said given direction, said oscillatory motion of said abrading member bodily with said sharpener carriage accomplishing movement of said abrading member into and out of engagement with one side of one edge of said bands, linkage means for reciprocating said sharpener carriage, motor means in driving association with said cylindrical abrading member for powering the rotation thereof relative to said sharpener carriage and in driving association with said carriage-reciprocating linkage means for actuation thereof, yielding means normally biasing said sharpener carriage for oscillatory positioning of said abrading member out of contact with said blades, means limiting the angular velocity of said oscillatory movement of said abrading member into contact with said blades, said two last-named means including an abutment shaft positioned for engagement by said sharpener carriage toward the one limit of oscillatory movement of the carriage relative to said sharpener carriage which corresponds to engagement of said abrading member with said bands, spring means biasing said abutment shaft to yieldingly oppose displacement upon engagement by said carriage, and a dashpot limiting the rate of displacement of said shaft against the biasing of said spring.

7. The combination with a base frame, first and second parallel, spaced-apart drum means rotatably mounted on said base frame, and endless slicing bands turning on and reaching between said first and second drum means, said slicing bands each having a cutting edge and said slicing bands each having first and second reaches both of which extend from a position in contact with and tangent to said first drum means to a position in contact with and tangent to said second drum means, and each of said first and second reaches having a twist of 180 degrees therein, of: a sharpener carriage, means mounting said sharpener carriage on said base frame for reciprocation in a given direction transversely of said bands and for oscillation in planes normal to said direction, said given direction being parallel to the axes of said drum means, a cylindrical abrading member rotatably mounted on said sharpener carriage for reciprocation and oscillation bodily therewith and for rotation relative thereto about an axis parallel to said given direction, said oscillatory motion of said abrading member bodily with said sharpener carriage accomplishing movement of said abrading member into and out of engagement with one side of one edge of said bands, linkage means for reciprocating said sharpener carriage, motor means in driving association with said cylindrical abrading member for powering the rotation thereof relative to said sharpener carriage and in driving association with said carriage-reciprocating linkage means for actuation thereof.

8. The combination with a base frame, first and second parallel, spaced-apart drum means rotatably mounted on said base frame, and endless slicing bands turning on and reaching between said first and second drum means, said slicing bands each having a cutting edge and said slicing bands each having first and second reaches both of which extend from a position in contact with and tangent to said first drum means to a position in contact with and tangent to said second drum means, and each of said first and second reaches having a twist of 180 degrees therein, of: a stationary shaft on said base frame extending parallel to the axes of said drum means, a sharpener carriage having a sleeve portion received for sliding and oscillating motion on said stationary shaft, a cylindrical abrading member rotatably mounted on said sharpener carriage for reciprocation and oscillation bodily therewith and for rotation relative thereto about an axis parallel to said stationary shaft, said oscillatory motion of said

abrading member bodily with said sharpener carriage accomplishing movement of said abrading member into and out of engagement with one side of one edge of said bands, spaced guide plates fixed to said stationary shaft and having apposite guiding faces normal to said stationary shaft, a drive shaft mounted on said sharpener carriage and extending radially outwardly with respect to said stationary shaft, an eccentric wheel eccentrically mounted on said drive shaft and engaged between said guiding faces for accomplishing reciprocation of said sleeve on said shaft by a mechanical relationship which is independent of said oscillatory movement of said sharpener carriage about said stationary shaft, motor means carried bodily on said sharpener carriage and in driving association with said cylindrical abrading member for powering the rotation thereof relative to said sharpener carriage and in driving association with said drive shaft, yielding means normally biasing said sharpener carriage for oscillatory positioning of said abrading member out of contact with said blades, means limiting the angular velocity of said oscillatory movement of said abrading member into contact with said blades.

9. The combination with a base frame, first and second parallel, spaced-apart drum means rotatably mounted on said base frame, and endless slicing bands turning on and reaching between said first and second drum means, said slicing bands each having a cutting edge and said slicing bands each having first and second reaches both of which extend from a position in contact with and tangent to said first drum means to a position in contact with and tangent to said second drum means, and each of said first and second reaches having a twist of 180 degrees therein, of: a stationary shaft on said base frame extending parallel to the axes of said drum means, a sharpener carriage having a sleeve portion received for sliding and oscillating motion on said stationary shaft, a cylindrical abrading member rotatably mounted on said sharpener carriage for reciprocation and oscillation bodily therewith and for rotation relative thereto about an axis parallel to said stationary shaft, said oscillatory motion of said abrading member bodily with said sharpener carriage accomplishing movement of said abrading member into and out of engagement with one side of one edge of said bands, spaced guide plates fixed to said stationary shaft and having apposite guiding faces normal to said stationary shaft, a drive shaft mounted on said sharpener carriage and extending radially outwardly with respect to said stationary shaft, an eccentric wheel eccentrically mounted on said drive shaft and engaged between said guiding faces for accomplishing reciprocation of said sleeve on said shaft by a mechanical relationship which is independent of said oscillatory movement of said sharpener carriage about said stationary shaft, motor means carried bodily on said sharpener carriage and in driving association with said cylindrical abrading member for powering the rotation thereof relative to said sharpener carriage and in driving association with said drive shaft.

10. The combination with a base frame, first and second parallel, spaced-apart drum means rotatably mounted on said base frame, and endless slicing bands turning on and reaching between said first and second drum means, said slicing bands each having a cutting edge and said slicing bands each having first and second reaches both of which extend from a position in contact with and tangent to said first drum means to a position in contact with and tangent to said second drum means, and each of said first and second reaches having a twist of 180 degrees therein, of: a sharpener carriage, means mounting said sharpener carriage on said base frame for reciprocation in a given direction transversely of said bands and for oscillation in planes normal to said direction, said given direction being parallel to the axes of said drum means, a cylindrical abrading member rotatably mounted on said sharpener carriage for reciprocation and oscillation bodily therewith and for rotation relative thereto about an axis parallel to said stationary shaft, said oscillatory motion of said

oscillation bodily therewith and for rotation relative thereto about an axis parallel to said given direction, said oscillatory motion of said abrading member bodily with said sharpener carriage accomplishing movement of said abrading member into and out of engagement with one side of one edge of said bands, linkage means for reciprocating said sharpener carriage, motor means in driving association with said cylindrical abrading member for powering the rotation thereof relative to said sharpener carriage and in driving association with said carriage-reciprocating linkage means for actuation thereof, yielding means normally biasing said sharpener carriage for oscillatory positioning of said abrading member out of contact with said blades, means limiting the angular velocity of said oscillatory movement of said abrading member into contact with said blades.

11. The combination with a base frame, first and second parallel, spaced-apart drum means rotatably mounted on said base frame, and endless slicing bands turning on and reaching between said first and second drum means, said slicing bands each having a cutting edge and said slicing bands each having first and second reaches both of which extend from a position in contact with and tangent to said first drum means to a position

in contact with and tangent to said second drum means, and each of said first and second reaches having a twist of 180 degrees therein, of: a sharpener carriage, means mounting said sharpener carriage on said base frame for reciprocation in a given direction transversely of said bands and for oscillation in planes normal to said direction, said given direction being parallel to the axes of said drum means, a cylindrical abrading member rotatably mounted on said sharpener carriage for reciprocation and oscillation bodily therewith and for rotation relative thereto about an axis parallel to said given direction, said oscillatory motion of said abrading member bodily with said sharpener carriage accomplishing movement of said abrading member into and out of engagement with one side of one edge of said bands, linkage means for reciprocating said sharpener carriage, motor means in driving association with said cylindrical abrading member for powering the rotation thereof relative to said sharpener carriage and in driving association with said carriage-reciprocating linkage means for actuation thereof, means to move said abrading member into and out of contact with said blade.
